UNITED STATES PATENT OFFICE.

JOHN L. HINNERS, OF PEKIN, ILLINOIS.

TRACKER-PIN FOR ORGANS.

SPECIFICATION forming part of Letters Patent No. 330,117, dated November 10, 1885.

Application filed January 2, 1885. Serial No. 151,818. (No model.)

To all whom it may concern:

Be it known that I, JOHN L. HINNERS, a citizen of the United States, residing at Pe-
kin, in the county of Tazewell and State of
Illinois, have invented certain new and use-
ful Improvements in Organ-Actions; and I
do declare the following to be a full, clear, and
exact description of the invention, such as
will enable others skilled in the art to which
it appertains to make and use the same, ref-
erence being had to the accompanying draw-
ings, and to the letters and figures of reference
marked thereon, which form a part of this
specification.

15 This invention relates to tracker-pins for
reed-organs; and its objects are to overcome
the defective operation of the ordinary wooden
pins, due to atmospheric changes, to reduce
the abrasion of such pins by friction, and to
20 protect them against being gnawed and
splintered by vermin.

It is well known to organists and organ-
builders that wooden tracker-pins often swell
25 so much in damp weather as to stick in their
courses; that they often shrink in dry air, so
as to cause rattling and escape of wind in the
apertures through which they pass; that they
wear away by friction, so as to produce un-
30 steady working of the valves operated by
them, and that they are often so gnawed and
splintered by mice, and even other vermin, as
to practically destroy them, and to obstruct
the valve-apertures into which the litter drops.
35 To overcome these several objections,
I reduce the circumference of the wooden pin
and incase it in a metallic tube, thus produc-
ing a combination of wood and metal in the
formation of a complete and single pin, and
40 guarding at once with practical efficiency
against each and all of the defects I have enu-
merated.

I may for some purposes make my tracker-
pin in the form of a simple metal tube with-
out filling, or filled only at and toward the
45 extremities, or I may use as filling some suitable
material other than wood; but the tracker-pin
shown and described herewith embodies the
construction that I have found best adapted
to the practical purposes of organ-building.

In the accompanying drawings, wherein like
50 letters refer to like parts, Figure 1 is a verti-
cal section of my tracker-pin applied to the
adjacent parts of an organ-action, and Fig. 2
a perspective of the pin with shoulder.

A is a round wooden pin fitting closely 55
within a metal tube, B, and slightly project-
ing from the tube at the upper end, so that
each pin may be filed as required to level the
row of finger-keys in finishing an organ.

C represents one of the finger-keys; D, the 60
reed-board through which the pin works; E
E, the sounding-board, having valve-slots e to
pass the air-currents to the reed-cells d; F,
the valve sliding on guide-pins f; and G the
spring which closes the valve when pressure 65
on the tracker-pin is removed. Should an
octave-coupler be introduced into the organ,
the dotted lines H indicate the relative place
and outlines thereof, and a represents the
70 shoulder formed upon the wooden core of the
pin, by which the coupler actuates the pin
when thrown into position by the usual stop
and mechanism for that purpose. When such
a shoulder is formed upon the pin, the tube or
75 jacket B must be made in two parts, one to fit
the wooden core above and one below the
shoulder, and I should also put a metal easing
or ferrule around the circumference of the
shoulder to protect it from being gnawed by
80 vermin.

Having thus described my invention, what
I claim to be new and useful, and desire to se-
cure by Letters Patent, is the following:

In a tracker-pin for reed-organs, the combi-
nation of the ordinary wooden pin with a 85
metal jacket fitting closely upon the same, said
jacket being flush with the pin at the lower
end, and slightly shorter than said pin at the
upper end, in the manner and for the pur-
poses herein described.

In testimony whereof I affix my signature in
presence of two witnesses.

JOHN L. HINNERS.
